UNITED STATES PATENT OFFICE.

EDWIN C. EWING, ALEXANDER GLASS, AND WILLIAM S. GRAFTON, OF WHEELING, WEST VIRGINIA, ASSIGNEES TO THE WHEELING CORRUGATING COMPANY, OF SAME PLACE.

DESIGN FOR A METALLIC FINISHING-PLATE.

SPECIFICATION forming part of Design No. 23,044, dated February 6, 1894.

Application filed January 8, 1894. Serial No. 496,189. Term of patent 7 years.

To all whom it may concern:

Be it known that we, EDWIN C. EWING, ALEXANDER GLASS, and WILLIAM S. GRAFTON, citizens of the United States, residing at Wheeling, in the county of Ohio and State of West Virginia, have invented and produced a new and original Design for Metallic Finishing-Plates, of which the following is a specification, reference being had to the accompanying drawing, forming part hereof, which shows a metallic finishing-plate designed according to our invention.

Our design consists of a metallic finishing plate A, divided into spaces or sections B, of equal area, by longitudinal ribs or ridges a. Each of the spaces or sections B, is divided into two principal parts by curved ribs C, which join the ribs a on opposite sides of the spaces B. In each of the spaces, and on both sides of the ribs C, there are a number of small, circular convex projections b. Each of the ribs a, on one side of or below the ribs C, is provided with a series of circular projections a', having concave centers a². These projections are arranged equal distances apart on each rib, and the projections in the parallel ribs are arranged in line with each other.

In the spaces B', on one side of or below the ribs C, there is an ornamentation consist-

ing of a fan-shaped projection D, similar in form to an Egyptian fan, and having a stem or handle d, with an enlarged or triangular outer end. The body of the fan D, has a curved rib d', around the inner end of the handle from which radiate a series of concave branches d². From the top of the fan body, projects a plume E, consisting of a central projection e, from which radiate on each side a series of curved arms or projections e'.

A snail-shaped rib or projection F, extends in each section from the two parallel ribs a, toward the handle of the fan.

The essential feature of our design is a metallic finishing plate divided into sections or spaces of equal area by ribs, or ridges, each of which sections has numerous convex projections and a fan-shaped projection joining a plume-shaped projection.

We claim—

The design for a metallic finishing plate herein shown and described.

In testimony whereof we have hereunto subscribed our names.

EDWIN C. EWING.
ALEXANDER GLASS.
WILLIAM S. GRAFTON.
